*Frederick Wittram,
INVENTOR.*

United States Patent Office.

FREDERICK WITTRAM, OF SAN FRANCISCO, CALIFORNIA.

Letters Patent No. 91,583, dated June 22, 1869.

IMPROVEMENT IN LETTER-BOXES.

The Schedule referred to in these Letters Patent and making part of the same.

To all whom it may concern:

Be it known that I, FREDERICK WITTRAM, of San Francisco, in the State of California, have invented a new and useful Improvement in "Letter-Boxes," to be attached to lamp or other posts, sides of buildings, doors, or other convenient places in the streets of towns or cities, in which letters may be deposited for the purpose of being collected by carriers and duly mailed.

To enable others skilled in the art to make and use this, my invention, I do hereby declare the following to be a full, clear, and exact description of the construction and operation of the same; reference being had to the annexed drawings, making a part of this specification, in which—

Figure 1 is a view of the letter-box;

Figure 3 shows the position of the cover when opened, to place a letter within the box;

Figure 2 shows the lid closed, with the space opened, through which the letter drops into the main portion of the box;

Figure 4 is an end view of the cover, and the rod connecting the same to the weighted ledge; and

Figure 5 is a front view of the same.

My object is to make a cheap, substantial letter-box, one that cannot easily get out of order, and into which the rain or snow cannot penetrate.

The box A is made of cast or other iron, or other desirable material, but it need not necessarily conform to the exact shape shown in the drawings.

a is the door opening into the box, and fastened in the usual manner, from which the letters deposited are taken by the proper person. This box may be made in one piece, with the exception of the lid or door.

B represents the cover of the box, and is curved, projecting over both the sides and ends of the upper portion of the box, marked b.

To this cover is firmly attached, by welding, riveting, or other convenient manner, the rod C; and to the lower end of said rod is also attached the weighted disk or ledge D.

These three parts may be cast or made in one piece and of uniform size, so that they may be readily duplicated in case of necessity, and applied to the box A.

At or near the centre of the rod C, as shown at X, a hole is left, into which rivets or screws F are applied, to firmly attach the same to the box A, at either end of the same; these rods being placed near the outer ends of the cover B, to admit of the adjustment above stated.

E is a piece of tin or other metal fastened to the inner side of the box A, in the position shown, running the whole length of the box, and projecting nearly to the upper side of the ledge D, against which the letters impinge as they are placed in the box. The box itself, however, can be made in such a manner as to avoid the use of this piece of metal E, without changing the principle of the invention.

The weighted disk or ledge D is so attached to the rod C, that it will always keep the cover or lid B closed, unless force is applied to the knob e to push back the lid or cover, when letters are to be deposited in the box, as shown in fig. 3.

Then, as soon as the letter is deposited therein, the lid or cover assumes the position shown in fig. 2, and the letter drops down into the main body of the box A.

It will be seen, therefore, from the drawings, that to form a perfect letter-box, according to my invention, the whole can be constructed in three pieces, each of which may be of uniform size and shape, easily put together, and repaired when necessary.

This invention may also be applied to ballot-boxes, without materially changing the mode of construction or operation, or safes for money, and other analogous purposes.

The letters are deposited in the following manner:

The lid or cover B is pushed back, and the letters or other mail-matter placed within the orifice d. They drop down upon the disk or ledge D, and are there retained until the hand is removed from the lid or cover. The weighted disk or ledge then drops and assumes a vertical position, and the letter falls into the bottom of the box A.

It is apparent, that by applying a weight to the lid or cover B, the box can be placed in an inclined position, and be operated in substantially the manner herein described, the weight being first removed from the disk or ledge D.

This box can also be applied for the purposes of reception of papers or packages for delivery.

What I claim as my invention, and desire to secure by Letters Patent, is—

The combination of the lid or cover B, rods C, disk or ledge D, with the box A, in the manner and for the purpose herein described.

FREDERICK WITTRAM.
